Inventor:
Arnold Fischer.

UNITED STATES PATENT OFFICE.

HOWARD L. FISCHER, OF ST. PAUL, MINNESOTA, ASSIGNOR TO BROWN & BIGELOW,
OF ST. PAUL, MINNESOTA, A CORPORATION OF MINNESOTA.

PENCIL.

Application filed September 17, 1920. Serial No. 410,879.

To all whom it may concern:

Be it known that I, HOWARD L. FISCHER, a citizen of the United States of America, residing at St. Paul, county of Ramsey, and 5 State of Minnesota, have invented certain new and useful Improvements in Pencils, of which the following is a specification.

My invention relates to pencils the primary object of which is to provide means 10 for supporting an eraser in a manner so that the pencil can be readily used with or without the eraser without departing from the general artistic or attractive appearance of the pencil.

15 In many instances it is very desirable to have an eraser associated with a mechanical pencil particularly where the construction of the same is such that the marking lead requires no sharpening, and the pencil is 20 constructed to wear for an indefinite period becoming an indispensable utility to the same extent as a fountain pen after one has become accustomed to the use of the same.

Some people using a pencil of this nature 25 would prefer to have it without an eraser, while others desire the eraser, particularly if it is positioned or associated with the pencil so that it can be readily used when needed.

30 The invention further provides means associated with the eraser for attaching it in a manner to hold it rigidly for use to a pencil or other utility where an eraser is required.

In the drawings forming a part of this 35 specification:

Figure 1 illustrates my pencil with an eraser attached thereto.

Figure 2 is an enlarged longitudinal cross section, a portion of the pencil being broken 40 away.

Figure 3 is a similar view to Figure 2 with some of the parts in a different position and only a portion of the pencil mechanism being broken away.

45 Figure 4 is an enlarged view of the operating member of the pencil when it is removed from the barrel and illustrating an eraser attached to the same.

Figure 5 is a cross section on the line 5—5 50 of Figure 3.

Figure 6 is an end view of the eraser.

Figure 7 is a side view of the eraser when disengaged from the pencil.

In the drawing the pencil A is provided 55 with a tubular barrel 10 in which the me-

chanical lead operating mechanism B is contained. The mechanism B is positioned within the casing in a manner to provide a circular space 11 about the same for extra marking lead. The forward end of the space 60 11 is closed by the supporting washer 12 which is attached to the mechanism B, while the closure 13 which is rigidly attached to the tubular threaded member 14 of the operating mechanism, serves to close the rear 65 end of the pencil lead space 11. The closure 13 is adapted to rigidly hold the threaded member 14 of the mechanism B in the casing 10 or to disengage it therefrom so as to remove it from the casing. 70

The closure 13 is threaded so as to engage the threaded bushing 28 which is rigidly secured in the rear end of the pencil casing. Obviously threads can be formed in the pencil casing 10, if desired, to engage the 75 threads on the closure 13 to hold it rigidly secured to the casing.

The operating mechanism B consists of two separable sections, namely the tubular threaded member 14 to which the washer 12 80 and closure 13 are attached, and an operating member 15 which is provided with an engaging head 16. The operating member 15 is rotatable within the threaded member 14 by engaging the head 16 when the parts of 85 the mechanism B are associated together either in the pencil casing or barrel 10 or out of it. These parts are collectively removable from the casing 10 or the operating member 15 can be removed independent of 90 the threaded member 14. This construction provides a mechanical operating means for the pencil A which can be sectionally removed from the barrel or in its entirety, and that the parts are interchangeable. The 95 barrel can be cleaned of any particles of marking lead which might break off therein and tend to clog the magazine by removing the mechanism B in its entirety.

The operating member 15 carries a lead 100 pusher 17 which extends through the longitudinal slot 18 so as to engage the threads of the member 14.

The operating head 16 is formed with a recess 19, while the eraser 20 is provided 105 with a screw 21, the same being countersunk or moulded in the body of the eraser to conceal the head of the screw with the threaded shank of the same extending out of one side of the eraser so that it can be 110

threaded into the opening 22 formed in the head 16. The erasers 20 are supplied with screws 21 embedded therein as illustrated in Figures 2, 6 and 7 so that a person using the pencil A can readily attach the eraser to the head 16.

The head 16 of each of the pencils A is provided with a recess 19 and a recess 22 so that an eraser 20 can be attached to the same if it is desired, however, if the user of the pencil does not desire an eraser the general appearance of the same would not be changed by leaving the eraser off and using the pencil without it. In this instance only the small hole 22 and the recess 19 would appear from the end of the head 16. In using an eraser 20 in connection with the pencil A when the body of the same is worn down the remaining portion together with the screw 21 can be removed from the opening 22 by a screw driver or other suitable instrument. The erasers 20 are supplied as illustrated in Figure 7.

The rear end of the tube 14 is formed with a slit 23 and the edge turned inward forming a shoulder 24 which is adapted to engage in the recess 25 formed in the shank of the head 16 to form a lock for holding the member 15 against free disengagement from the member 14, while the closure is formed with the recess 26 which will accommodate the expansion of the slit rear end of the member 14. The lead pusher 17 is provided with spring means which forms a frictional engagement between the member 14 and the member 15 and thus provides sufficient friction between these members to hold the member 15 from sliding freely in the threaded member 14 while the rear end 24 engages in the recess 25 to lock the operating member with its head therein against free disengagement from the same.

It is desirable to make pencils of this nature out of gold and silver tubing and therefore it is highly essential that any eraser or its attachment to the pencil be not only simple but of such a nature that the pencil can be used with or without the same without detracting from the artistic appearance of the same and it is obvious that the head 16 can be formed of suitable material which is not effected by the eraser so that it will not become discolored or tarnished when the eraser is used in connection therewith.

While I have illustrated a pencil of a particular construction with an eraser attached thereto in a certain manner I desire to have it understood that I do not wish to confine myself to the particular construction illustrated, as the invention may be carried out by other means and applied to uses other than those above set forth within the scope of the following claims:

I claim:

1. A mechanical pencil comprising a cas-

ing, sectional lead propelling means positioned in said casing in a manner to provide a space around said propelling means for extra leads, said propelling means constituting a threaded member, a lead pusher 70 adapted to cooperate with the threads of said threaded member and a slotted operating member adapted to carry said lead pusher, a closure for the rear end of said space, an operating member forming one of 75 the sections of said propelling means, and a lock in said closure adapted to lock said operating member in said pencil.

2. A mechanical pencil including a barrel, a propelling mechanism adapted to be contained in said barrel, comprising a tubular threaded member positioned within the barrel to form a space thereabout for extra marking leads, a closure secured to the rear end of said threaded member, an operating 80 member, a threaded lead pusher carried by said operating member adapted to engage said tubular threaded member, removably positioned within said threaded member and a lock associated with said closure and 90 the operating end of said operating member to prevent the free disengaging of said operating member from said threaded member.

3. A pencil including a barrel, a threaded member positioned within said barrel to form a space thereabout for extra marking leads, a shoulder forming a closure on the rear end of said threaded member for said extra marking lead space and adapted to 100 lock said threaded member in said barrel, an operating member having an engaging head projecting from the rear end of said pencil, a lead carrier in said operating member adapted to cooperate with the threads of said threaded member, and spring locking means adapted to engage said operating member adjacent said engaging head to hold it against free disengagement from said pencil. 110

4. A mechanical pencil, including a barrel, a propelling mechanism adapted to be contained in said barrel comprising a threaded tubular member, means secured to either end of said tubular member adapted to form a space thereabout for extra marking leads, spring fingers formed on one end of said threaded member, an operating member removably positioned within said threaded member, a lead pusher slidably held within said operating member having resilient means adapted to hold said pusher into engagement with said threaded tube, said spring fingers on said threaded member adapted to engage said operating member 115 to lock it against free longitudinal movement in operating position in said pencil. 120

5. A pencil including a casing, a sectional lead propelling means adapted to be positioned in said casing in a manner to form 125 130

- a magazine space thereabout, the casing forming the outer wall of the magazine, a closure collar secured to one of the members of said propelling mechanism, a recess 5 formed in said closure collar, resilient engaging means projecting into said recess, an operating member extending through said recess and adapted to be engaged by said resilient means to hold said operating member 10 freely rotatable and against longitudinal movement in operating position.
6. A mechanical pencil including a casing, a tubular threaded member adapted to be positioned in said casing in a manner to 15 form a lead chamber thereabout, an enclosure collar secured on said threaded member, adapted to rigidly attach said threaded member to said casing, an operating member extending through said threaded member, a lead pusher having means adapted to 20 hold said pusher in engagement with said
- threaded member and slidably positioned within said operating member, an engaging head formed on said operating member, an annular recess formed in said operating head and means positioned in said closure collar adapted to engage in said annular recess to form a lock for holding the operating parts of said pencil together in operation. 25
7. In a mechanical pencil, comprising a casing, a tubular threaded member and a tubular operating member, said threaded and operating member constituting the propelling mechanism of said pencil, and both being 30 separable from said casing, together or singly, and locking means interposed between said members of said propelling means adapted to permit free rotation of said operating member and to retard separation of 35 the parts of said propelling mechanism.

HOWARD L. FISCHER.
